United States Patent Office

Des. 185,247
Patented May 19, 1959

185,247

BOTTLE

George Dan Taran, Honolulu, Territory of Hawaii

Application January 13, 1959, Serial No. 54,159

Term of patent 3½ years

(Cl. D58—9)

FIG. 1

FIG. 2

FIG. 3

FIG. 4

FIG. 5

FIG. 6

Fig. 1 is a front elevational view of a bottle, showing my new design;

Fig. 2 is a rear elevational view thereof;

Fig. 3 is a side elevational view thereof taken from the right side of Fig. 1;

Fig. 4 is a side elevational view thereof taken from the left side of Fig. 1;

Fig. 5 is a top plan view thereof; and

Fig. 6 is a bottom plan view thereof.

I claim:

The ornamental design for a bottle, substantially as shown.
